Walter H. Randall, Waterville, Maine, assignor, by mesne assignments, to The Canal National Bank of Portland, Portland, Maine, a national banking association of the United States, and William B. Nulty, Portland, Maine, as trustees

Application April 22, 1950, Serial No. 9,421

Term of patent 14 years

(Cl. D58—13)

To all whom it may concern:

Be it known that I, Walter H. Randall, a citizen of the United States, residing at Waterville, county of Kennebec, State of Maine, have invented a new, original, and ornamental Design for Compartmented Tray for Fruit and Other Articles, of which the following is a specification, reference being had to the accompanying drawing, forming part hereof.

In the drawing:

Fig. 1 is a top plan view of a compartmented tray for fruit and other articles, showing my new design.

Fig. 2 is a longitudinal vertical section taken on line 2—2 of Fig. 1.

Fig. 3 is a transverse vertical section taken on line 3—3 of Fig. 1.

I claim:

The ornamental design for a compartmented
tray for fruit and other articles, as shown.

WALTER H. RANDALL.
